UNITED STATES PATENT OFFICE.

CHARLES W. HUNT, OF WEST NEW BRIGHTON, NEW YORK.

CAR-TRUCK.

SPECIFICATION forming part of Letters Patent No. 452,135, dated May 12, 1891.

Application filed February 16, 1891. Serial No. 381,597. (No model.)

To all whom it may concern:

Be it known that I, CHARLES W. HUNT, a citizen of the United States, residing at West New Brighton, in the county of Richmond 5 and State of New York, have invented an Improvement in Railway-Car Trucks, of which the following is a specification.

In railway-car trucks such as shown in my patent, No. 347,936, a single axle with a pair 10 of wheels upon it has been pivoted at the central part by a sleeve around the axle and a triangular frame hinged to the frame of the car. In this construction of car-trucks there is often considerable bending strain upon the 15 king-bolt, especially so when the journal-boxes are connected by links to the frame.

My present invention is intended to relieve the king-bolt from lateral or bending strain; and it consists in an arm extending 20 out from the sleeve and bearing against guides upon the frame, so that the strength of the arm or bearer is availed of for maintaining the bearer and king-bolt in a vertical position and preventing the bending-strain 25 coming upon the king-bolt.

In the drawings, Figure 1 is a plan view representing the present improvement as applied to a pair of truck-wheels, and Fig. 2 is a vertical section at the line $x-x$ of Fig. 1.

30 The wheels B are upon the axle C, and there is a cross-bearer or sleeve E between the two wheels and over the axle, and the truck or frame A may be of either wood or iron, and it may be either between the wheels or out- 35 side of the same, and any suitable connection may be provided between the axle-boxes and the frame. The king-bolt 5 serves to connect the sleeve or bearer E to the car, and this king-bolt 5 might pass into a cross-beam 40 of the car itself; but I prefer to employ a triangular frame L, through which the king-bolt 5 passes, and the base of the triangular frame L is represented as connected by the cross-shaft or hinges 4 to the car or truck frame.

45 An arm G extends out laterally from the sleeve or cross-bearer E, and such arm passes in between two supports 6 and 7. These supports 6 and 7 may be directly one above the other, or they may be one in front of the 50 other. I have represented such supports 6 and 7 as upon the triangular frame L, and

the arm G between such supports is free to be moved by and with the sleeve or bearer E, as such bearer E and the axle assume a more or less inclined position to the center of the 55 car, and there should be stops upon the supports 6 and 7 to limit the movement of the arm G in either one direction or the other. These supports 6 and 7 might be upon the under side of the car in cases where the triangular frame L is dispensed with, and under all circumstances the pair of truck-wheels, 60 axle, and sleeve can swing upon the king-bolt 5 in either passing around a curve or in traveling upon a straight track, and the arm G 65 between the supports 6 and 7 relieves the king-bolt of any strain tending to bend such king-bolt, because the arm G holds the bearer E in its proper upright position, but at the same time allows for the turning of the parts 70 upon the king-bolt.

In cases where springs are applied between the hanging links and the axle-boxes, it is preferable to make use of the triangular frame L and to provide the supports 6 and 7 75 for the arm G upon such frame, because the parts are held in their proper relative position at the same time that a rising-and-falling motion of the car-body or truck-frame upon the springs is allowed for. The flanges 80 of the car-wheels B are on the outside, as shown, because with one pair of wheels and an axle swinging upon the king-bolt the outer flanges are found in practice the most reliable for giving the proper horizontal 85 movement or swing to the axle in entering and leaving curves in the track.

I claim as my invention—

1. The combination, with the car wheels and axle, of a bearer on the axle and between 90 the wheels, a pivot connecting the bearer with the car body or frame, and an arm extending out from the bearer, and supports against which the arm is permitted to move horizontally and by which the bearer is retained in 95 normal position, substantially as set forth.

2. The combination, with the car-frame and the pivoted frame, of an axle and pair of wheels, a sleeve or bearer over the axle between the wheels, a king-bolt connecting the 100 bearer and the frame, an arm extending out from the bearer, and supports upon the frame,

between which the arm is allowed a limited horizontal movement, substantially as and for the purposes set forth.

3. The combination, with the car or truck frame and the frame pivoted thereto, of an axle and pair of car-wheels with outside flanges, axle-boxes, springs, and suspending links, a bearer over the axle, a king-bolt connecting the bearer and the frame, an arm extending out from the bearer, and supports for

the arm, between which such arm is allowed a limited horizontal motion, substantially as set forth.

Signed by me this 12th day of February, 1891.

CHAS. W. HUNT.
